CLAIM

The ornamental design for a slide out bed floor with integrated brake lights for electric vehicle, as shown and described.

DESCRIPTION

FIG. 1 is a perspective view of a slide out bed floor with integrated brake lights for an electric vehicle, in a closed position;

FIG. 2 is a perspective view thereof, with bed extender retracted and barn-door tailgates in a 90 degree open position;

FIG. 3 is a perspective view thereof, with bed extender retracted and barn-door tailgates in a 180 degree open position;

FIG. 4 is a perspective view thereof, with bed extender extended, with barn-door tailgates in a 90 degree open position and secured to barn-door tailgates, and with inner tailgates stowed; and,

FIG. 5 is a perspective view thereof, with barn-door tailgates in a 90 degree open position and secured to barn-door tailgates, and with inner tailgates deployed.

The broken lines showing a vehicle illustrate environmental structure which forms no part of the claimed design. The broken lines on the slide out bed floor with integrated brake lights illustrate portions of the article which form no part of the claimed design.
